COMPRESSOR MECHANISM

3. Sheets—Sheet, 3

UNITED STATES PATENT OFFICE

FRED D. HOLDSWORTH, OF CLAREMONT, NEW HAMPSHIRE, ASSIGNOR TO SULLIVAN MACHINERY COMPANY, A CORPORATION OF MASSACHUSETTS

COMPRESSOR MECHANISM

Application filed April 14, 1924. Serial No. 706,583.

This invention relates to compressor mechanisms, and more particularly to portable compressors, although the same may be used wherever it is desired to reduce vibration to a minimum.

An object of the invention is to provide an improved portable compressor. Another object is to provide in general an improved portable compressor and portable mounting therefor. A further object is to provide an improved compressor mechanism having cooperating elements thereof so arranged that vibration will be reduced to a minimum. A further object is to provide a multi-cylinder compressor which is extremely compact. A further object is to provide an improved valve mechanism which is readily accessible, a still further object being to provide an improved type of valve, parts of which are held by exterior means. A further object is to provide improved means for unloading the various cylinders of the compressor in steps to assist in reduction of vibration. A further object is to provide an improved oiling system for a compressor whereby the bearings will be automatically oiled.

In the accompanying drawings I have shown for purposes of illustration one form which my invention may assume in practice.

30 In these drawings,—

Fig. 1 is a plan view of the compressor supported upon a portable mounting, parts being omitted to facilitate illustration.

Fig. 2 is a side elevation of the same.

35 Fig. 3 is a vertical transverse sectional view, partially in elevation, taken on line 3—3 of Fig. 2.

Fig. 4 is a vertical transverse section on line 4—4 of Fig. 2.

40 Fig. 5 is a longitudinal vertical section on line 5—5 of Fig. 4, part of the mechanism being omitted.

Fig. 6 is a longitudinal vertical section 45 through the valve mechanism.

Figs. 7 and 8 are modified forms of compressors.

50 Fig. 9 is a transverse view taken on line 9—9 of Fig. 5, the details of which are applicable to the various forms of units shown.

Fig. 10 is an approximate crank effort diagram.

In my improved type of portable compressor I provide a vehicle having a frame 1 mounted upon front steering wheels and rear wheels 2 and 3, respectively. Mounted within the forward portion of the frame 1 is a usual driving motor 4 having all the accessories necessary for its normal operation but which need not be described here. Disposed to the rear of the engine 4 is my improved compressor 5, the crank shaft 6 of which is connected to the engine shaft 7 by an improved form of flexible shaft connector 8 shown in Fig. 5 as comprising an external gear in mesh with an internal gear connected respectively to the shafts 6 and 7.

55 In order to further carry out the compact arrangement it is to be noted that the shaft connection 8 is disposed within a recess 23 of the flywheel, thereby allowing the compressor and engine to be brought exceedingly close to each other. It is also to be noted that the flywheel has a cover 24, thereby giving full protection to the operator. This connecting means will be more fully described later where the novelty of certain structure embodied therein will be more apparent.

60 The compressor which forms one phase of this invention comprises a crank case 10 having a lower cover 11 with an oil reservoir 11^a and oil pockets formed therein so that the lubricant may be supplied to various parts of the compressor, as by the usual splash system. In portable compressor outfit there is no fixed foundation and hence it is highly desirable to provide a compressor in which vibration is reduced to a minimum; otherwise the whole outfit including the engine, frame and receiver will be shaken and all the connections to these various elements thereby loosened, thus lessening the life of the outfit as a whole. In a stationary outfit, the cooperating elements such as the engine and receiver would be mounted on heavy substantial supporting structures, and these supporting structures would hold the engine and receiver steady, so that they would not 65 70 75 80 85 90 95 100

be materially affected even by a compressor which might have considerable vibration. It is thus seen that the applicant has been confronted with a really serious problem. To 5 overcome such defects I use a V-type compressor having a plurality of cylinders 12, herein four, two of which are disposed on each side of a vertical plane passing through the crank shaft 6. Mounted within the cylinders are usual pistons 13 connected to crank shaft 6 as by connecting rods 14. As clearly shown in Fig. 5, cylinders lying in the same transverse plane have their connecting rods connected to the same crank of the crank 10 shaft. Thus for a four-cylinder compressor a two-throw crank is all that is necessary. In order to further reduce vibration a compressor flywheel 15 is mounted on the rear end of crank shaft 6, while the engine flywheel 16 is disposed adjacent the front end of the compressor, thus acting as a flywheel for both the engine and the compressor. If the flywheels were all located at the front of the compressor, the crank shaft would be subjected to greater torsion at the front end and would thus tend to throw the forward crank out of the plane in which the rear crank lies. When the two cranks are idle they lie in the same plane and hence balance each 15 other. However, by the applicant's construction any tendency to twist the cranks out of the same plane and thus cause vibration is reduced to a minimum because the energy stored in the rear flywheel will assist 20 in rotating the crank shaft from the rear end during compressing action by the piston, thereby reducing the tendency for any wide range of torsion and thus keeping the cranks in as near the same plane as is possible. It 25 is to be understood that when the cranks do not lie in the same plane the weight of the cranks do not balance each other and thus set up serious vibration. A modified form 30 of compressor is shown in Fig. 7, which like the V-type compressor, allows a dual function to be performed, namely that of reducing vibration to a minimum and providing an exceedingly compact arrangement, thereby allowing ample overhead space within 35 which auxiliary means may be disposed. Such an arrangement thus permits the many advantages before mentioned while at the same time not requiring any compressor capacity to be sacrificed. The compressor as 40 shown is of the opposed cylinder type having cylinders 75, the pistons therein being driven by a four-throw crank shaft 76, thereby insuring perfect balance.

In order to adequately lubricate the bearings I have provided an improved oiling system which utilizes both a splash and gravity feed. The left hand bearing 16' as shown in Fig. 5 receives its oil by splash feed from the flywheel as by oil groove 17. To lubricate 45 the other bearings as shown in Fig. 5 I pro-

vide a pocket 18 transversely disposed adjacent the upper portion of the flywheel where it will readily catch oil thrown off from the same. A reservoir 19 is disposed along the uppermost portion of the crank 70 casing 10 and between the cylinders on the opposite sides, this reservoir having communication with the pocket 18 as by a passage 20. In order to lubricate the various bearings other than the rear bearing, passages 21 are formed in the bottom of the base 75 of the chamber 19 directly over the front bearing 16' and the connecting rod bearings 22.

The inlet and discharge valve mechanism 80 for each cylinder is supported by a head plate 25 adapted to cover the upper end of the cylinders, and a casing 26 which has formed therein a longitudinal bore 27 and a chamber 28. The bore 27 and the chamber 28 are in communication, a flange 29 being formed between the two. Passage 30 opens out of bore 27 into the cylinder 12. Discharge chamber 32 leads out of chamber 28, and at its other end has connection with a receiver 33 as by a pipe connection 34. The valve mechanism proper for controlling the flow from the cylinder comprises a valve cage 35 having a flange seated upon the flange 29 and ports 36 disposed therein. A valve 37 adapted to close and open the ports 36 is held in position by a suitable guard 38 which in turn is fixed to the cage 35 by suitable securing means. As shown, the guard is secured to the cage 35, and the whole is secured in position with the flange seated upon the flange 29 by a nut and bolt connection 39. The bolt is threaded into the cage 35 and also projects outwardly through an opening 40 in the rear wall of the casing 26. A nut 41 90 engages the outer end of the bolt 39 to hold the cage 35 in fixed relation to the flange 29. Opposed to the cage 35 is a second cage 44 adapted to project inwardly of the bore 27 and held therein as by bolts or other suitable means, the valve 45, which is adapted to open and close the ports in the cage 44, being held in position by a guard 46 and nut and bolt connection 47. Means are provided 95 for positively actuating the valves 45 so as to keep the ports open and thereby unload the compressor, this means comprising an outwardly extending member 50 having a chamber 51 therein which is aligned with and has communication with the interior of the cage 44, and which has communication with the atmosphere as by ports 52. Projecting within the member 50 is a cylinder member 55. Actuating fluid is delivered at suitable times 100 by a pipe 60 to the interior of the cylinder member 55 to act upon a piston which is adapted to move longitudinally therein against the action of a spring. The stem 54 of the said piston carries a plurality of valve 105 110 115 120 125 130

engaging fingers 53 of the usual type which extend within the cage 44 to cooperate with the valves 45 in the manner specified above. The delivery of actuating fluid to the cylinder member 55 is controlled by a Judson valve 57 the well known function of which is to allow flow of fluid from the receiver to the unloading mechanism when receiver pressure reaches a predetermined high value thereby to unload the compressor until the receiver pressure falls to a predetermined low value whereupon the Judson valve allows release of the actuating pressure fluid for the unloading mechanism.

15 In order to further reduce vibration, the applicant proposes to use a novel unloading arrangement whereby two cylinders will be unloaded at a time, the position of the cylinders selected being such that the thrust on the crank shaft due to compressing will be kept at a minimum and distributed throughout the length of the crank shaft. To accomplish this, the applicant unloads both cylinders on one side of the longitudinal vertical plane and pumps with the cylinders on the other side. When it is desired to completely unload the compressor, the latter cylinders are then unloaded. This unloading is accomplished by Judson valves 57 which control flow of fluid to the cylinders 55 of the above named pair of cylinders 12 as by pipes 60, flow of fluid to the Judson valves being through a pipe 61 connected to the receiver 33. It is to be noted that the valve mechanism has its axis disposed in the same longitudinal plane as the motor which thereby reduces the overall width of the compressor to a minimum.

It is to be noted that in my improved 40 portable compressor I have provided an extremely compact arrangement of all the elements. For instance, in Fig. 3 the gasoline tank 65 or other auxiliary apparatus, is disposed in a very low position over the compressor due to the V-type compressor and within the vertical limits of the receiver 33. I have also provided an arrangement whereby a relatively large receiver may be used and yet which will not increase the overhead 45 dimension, it being noted that the receiver 33 is fixed to angle irons 66 secured at one end to the frame 1 and at the other end to the receiver 33 intermediate its ends as by angle braces 67. Thus the top of the receiver 50 is no higher than the uppermost point in the whole outfit which is a decided advantage, namely, that the portable outfit will not be top heavy and thus reduce vibration to a minimum. In order to provide the simplest 55 form of piping between the compressor and receiver it will be noted that pipe 34 leading from each compressor block terminates in a common upwardly extending pipe 68 which has communication with the receiver as by 60 a horizontal pipe 69. The usual blowoff

valve 70 extends upwardly from pipe 68 instead of being mounted on the receiver. This makes it unnecessary to drill additional holes within the receiver. It will herein be noted that the wheeled truck 1 is provided with a 70 suitable roof and side cover members housing the engine and compressor units and the associated mechanism.

It is to be noted that the oil passage 19, in the form of the compressor shown in Figures 5 and 7 comprises a channel opening directly to the exterior and is covered by a transversely V-shaped plate 77 which can be held in position by any suitable means such as screws and made leak-proof by any usual gasket means. In the modified form of the compressor shown in Fig. 8, the same has vertically disposed cylinders. It has a flywheel disposed on the rear end of its crank shaft the same as the compressors shown in 85 Figs. 5 and 7 so as to obtain the nicety of balance due to the particular disposition of the same relative to the engine flywheel 16. In this modified form of the compressor, an oil pipe 78 will conduct the fluid from the 90 reservoir 18 to the front end of the compressor instead of having a channel.

It is well known that in portable compressors vibration is very noticeable for there is no firm or fixed foundation, and hence it is 95 highly desirable to reduce all causes for any vibration, for it is obvious that the several elements which go to make up the compressor outfit will otherwise soon be shaken loose. It is found that in my improved arrangement, to 100 be described, it is possible to eliminate one of the causes of such vibration. This arrangement consists in making the engine and compressor crank shafts have a definite angular relation so that the maximum tangential force exerted on a compressor crank will occur substantially when a maximum tangential force is exerted on one of the engine cranks caused by an explosion in the engine cylinder. In Fig. 10 the line 90 represents 105 generally a crank effort diagram of one engine crank, it being noted that during compression of the fuel the line 90 will fall below the zero line 91 and after it has reached the head-end dead center, an explosion will occur causing the tangential force upon the crank shaft to increase to a maximum and then decrease as the same approaches its crank-end dead center. The crank effort diagram 110 also generally indicates at 92 the tangential force of a compressor crank and is shown as having a maximum crank effort at 93. It is to be noted that in the engine diagram that portion which extends above the zero line 91 will 115 be of a positive driving nature, tending to 120 turn the crank in one direction, while the portion of the compressor diagram disposed above the zero line 91 will be tending to retard movement of the crank shaft. The diagrams are placed on the same side so as to 125 130

show more clearly how the resisting and driving forces in the two crank shafts will rise and fall together. It has been discovered that by disposing the cranks of the engine 5 shaft at an angle of approximately 90° with respect to the cranks of the compressor shaft, the maximum resisting force is offered by the compressor substantially simultaneously 10 with the production of the maximum driving force by the engine. The result, as shown in Fig. 10, is that the forces opposing each other within the shafts will reach their maximum and minimum values substantially simultaneously, resulting in the lack of necessity 15 for storing an excessive amount of energy in the engine or compressor flywheels. Thus the engine shaft will not first be subjected to a high stress to store up energy in the flywheel and then the compressor shaft subjected 20 to a high stress during compressing action by the energy stored in the flywheel, which operation would cause torsion in first one shaft and then the other, thus causing a very noticeable vibration. By my improved 25 arrangement such disturbances are very noticeably diminished. It will of course be understood that my improved arrangement is particularly adapted for a one, two or four cylinder compressor, but would also be of material advantage in other types. To make 30 sure of obtaining the proper angular relation of the compressor and engine crank shafts as required to accomplish my improved result, I have shown improved means for ensuring 35 such a relation.

This means comprises the connection 8, as shown in Fig. 5, this connection includes as 40 one of its members an internal gear 80 bolted to the flywheel 16 of the engine as by a plurality of equally spaced bolts 81 and a bolt 82 unequally spaced with respect to the other bolts. Hence the internal gear 80 can only have one position relative to the crank shaft 7 as it would be impossible to place said gear 45 in another position. Disposed on the compressor crank shaft 6 is a spur gear 83 adapted to mesh with the internal gear 80. In order that the engine and compressor crank shafts shall have only one possible angular relation 50 for assembly, a pin 84 is positioned within a hole drilled in the spur gear between adjacent teeth, while one tooth of the internal gear is cut out leaving a vacant space 85. Thus, in assembling these gears the pin 84 will need 55 to be positioned so as to come within the vacant space 85, and it will be noted that such position is the only one that it can have, for in attempting to cause the same to take any other position the pin 84 would engage one of 60 the internal gear teeth. It will of course be understood that any number of different means may be employed to accomplish this same result, this disclosure herein forming only one of the several means.

65 While I have in this application specifically described three forms which my inven-

tion may assume in practice, it will be understood that these forms of the same are shown for purposes of illustration and that the invention may be modified and embodied in various other forms without departing 70 from its spirit or the scope of the appended claims.

What I claim as new and desire to secure by Letters Patent is:

1. A portable compressor outfit comprising an engine having a flywheel provided with an axially disposed recess, a compressor comprising a shaft, and flexible connecting means disposed within said recess for transmitting torque from the motor to the shaft of the compressor. 75

2. In a portable compressor outfit, in combination, an engine having a power shaft, a compressor comprising a shaft disposed in alinement with said power shaft, and a combined flywheel and flexible coupling having members fixed to the adjacent ends of said shafts, said combined flywheel and flexible coupling comprising a flywheel member provided with an axially disposed recess and a flexible coupling member secured thereto and disposed within said recess. 85

3. A portable compressor comprising a crank case, a crank shaft having bearings, angularly disposed cylinders with pistons therein, a flywheel, a reservoir adjacent said flywheel to hold an initial supply of oil which surrounds said wheel and a second reservoir adapted to catch oil thrown up by said wheel, a chamber disposed in said crank case and having communication with said reservoir, and passage means between said angularly disposed cylinders and leading from said chamber near the bearings to be lubricated to allow flow of oil thereto from said chamber. 95

4. A compressor mechanism comprising angularly disposed cylinders and pistons, a crank shaft for driving said pistons, a flywheel on said crank shaft, a crank case formed with a reservoir portion to hold an initial supply of oil which surrounds said wheel and a basin portion disposed transversely of said flywheel so as to catch oil thrown up by said wheel, and a passage formed in said crank case parallel with the axis of the crank shaft and adapted to allow lubricant to be transmitted therethrough from said basin portion to parts to be lubricated. 105

5. A compressor comprising a plurality of cylinders, reciprocable pistons cooperating therewith, a single crank shaft for causing reciprocation of said pistons, and unloading means for unloading the cylinders in sets so chosen that in the cycle of the said 115 crank shaft the times of maximum compression of the cylinders selected for unloading are equally spaced. 120

6. A compressor comprising a plurality of angularly disposed cylinders, reciprocable 130

5   pistons cooperating therewith, a single crank shaft for causing reciprocation of said pistons, and unloading means for unloading the cylinders in sets so chosen that in the cycle of the said crank shaft the times of maximum compression of the cylinders selected for unloading are equally spaced.

10   7. A compressor comprising a plurality of angularly disposed cylinders and pistons, driving means therefor comprising a crank shaft and connecting rods for the pistons, a plurality of rods being actuated by each crank, and unloading means adapted to unload one set of cylinders at a time, a set including only one cylinder in driving relation with each crank.

15   8. A compressor comprising a plurality of angularly disposed cylinders, reciprocable pistons cooperating therewith, driving means therefor including driving connections for the pistons so arranged as to equalize the distribution of the impulses for the various pistons throughout the cycle of the driving means, and unloading means for unloading the cylinders in sets so chosen that in the cycle of the said driving means the times of maximum compression of the cylinders selected for unloading are equally spaced.

20   9. A portable compressor outfit comprising a frame, an engine disposed to the front end thereof having a crank shaft, a compressor also having a crank shaft and a plurality of angularly disposed cylinders, said crank shafts being in alinement, a vertically disposed fluid storage tank carried intermediate its ends by said frame and to the rear of and substantially in alinement with said compressor, and a second fluid storage tank for said outfit disposed above said compressor and within substantially the vertical limits of said first fluid storage tank.

25   10. In combination, a compressor and driving means therefor both of which have a crank shaft with relatively angularly disposed crank arms, and means for correlating the said shafts so that the maximum tangential forces on the respective shafts occur substantially simultaneously comprising connecting means formed to have a single relation in which they can be assembled.

30   11. The combination comprising a compressor having a crank shaft, a cylinder and a piston, and a reciprocating piston type of driving motor therefor having a crank shaft, the crank arms of the respective shafts constituting driven and driving arms, and means for correlating the said shafts comprising connecting means formed with intermeshing portions, one of said portions preventing assembly of said connecting means in other than a single relation.

35   12. A compressor comprising a plurality of cylinders grouped in pairs, the cylinders of each pair being disposed with their longitudinal axes at an angle, a piston cooperating

40   with each cylinder, a connecting rod cooperating with each piston, a crank shaft having a crank for each group, the connecting rods of the respective groups being connected to the corresponding cranks, and unloading means adapted to unload simultaneously one cylinder of each group.

45   13. A compressor comprising a plurality of cylinders and pistons, means for reciprocating said pistons in said cylinders comprising a crank shaft having its cranks disposed at an angle of 180° with respect to each other, a pair of said pistons being connected to each of said cranks, and unloading means adapted to unload one cylinder of each pair independently of unloading of the other cylinder of each pair.

50   In testimony whereof I affix my signature.
